UNITED STATES PATENT OFFICE.

STEPHEN WM. SMITH, OF BROOKLYN, NEW YORK.

SWEEEPING-MACHINE.

Specification of Letters Patent No. 22,678, dated January 18, 1859.

To all whom it may concern:

Be it known that I, STEPHEN WM. SMITH, of Brooklyn, Kings county, New York, have invented a new and useful improvement in 5 Sweeping-Machines; and I do hereby declare the following to be a full, clear, and exact description thereof, reference being had to the accompanying drawings, figures, and letters of reference thereon, making part 10 of this specification.

Of the said drawings, Figure 1 denotes an end view of my improved machine, with the end plate removed to show the mechanism. Fig. 2, is an underside view of the same. 15 Fig. 3, is a vertical transverse section. Fig. 4, is an end view showing the door for removing the dirt and the adjusting mechanism for the rotating brush.

Similar letters of reference indicate like 20 parts in all the drawings.

The various machines heretofore constructed have only been able to sweep carpets, which surfaces were soft and elastic, and in this operation there have been many 25 objections. In machines where the brush is driven by means of friction derived from a toothed wheel resting on the carpet and working a pinion it is found that the driving wheel will often take up crumbs of 30 bread, pieces of dirt or pins which stop the movements of the gears by clogging and mutilates the carpet. In the Harris machine where the brush is driven by a padded wheel, if the wheel is pressed against the 35 brush shaft sufficiently hard to rotate it there is much friction, and any inequalities in the padded wheel will cause the brush to stop or require an additional force on the part of the operator to force the machine 40 along. The same may be said of machines driven by means of a traction wheel and bands. They constantly require tinkering. The great trouble is in the propelling mechanism which is of the utmost importance in 45 machines of this character.

My machine is designed as an improvement on the Harris machine patented Oct. 5th, 1858 which patent I own.

The nature of my improvement consists 50 first in the combination and arrangement of propelling mechanism. Second in an arrangement of means for adjusting the rotating brush, and third in a means for effectually preventing the dust from rising during

the operation of sweeping, all of which will 55 be more fully hereinafter set forth.

To this end, and to enable those skilled in the art to make and use my invention I will proceed to describe its construction and operation. 60

A represents a semicylindrical metallic casing.

B B, are the heads properly attached by means of grooves or otherwise, one of which is provided with a door c, hinged at (g g) 65 for emptying the sweeper of its dirt.

D is the rotating brush which has its journal (a a) in the adjustable boxes (b b).

E is the padded traction wheel having its bearings at (c c) which is attached to and 70 moves with a toothed gear F, which drives a pinion G secured to the brush shaft near (a) Fig. 2.

H is a roller, being in bearings (e e) in the box M, for keeping that side of the 75 sweeper steady and at the desired height. I, is another small roller which is secured to and rotates in a frame piece (d) which is attached to the end piece B, by screws, as shown in Fig. 2. 80

J is the dirt pan.

K is the box for adjusting the brush which may be done both vertically and laterally by means of the elongated holes or slots 85 through which the screws pass.

L is the curtain which extends around three sides of the machine and is on a plane with the circumference of the rollers H and I, and effectually prevents the dust from 90 rising during the operation of sweeping.

N is a segment secured to the dust pan which fits the radius of the brush and causes the dirt to be carried forward and deposited into the dirt pan J. O, is another segment secured to the casing A, and corresponding 95 to the radius of the brush to prevent any dirt from being carried over or past its edges by the brush in its revolutions.

The machine is operated by a handle attached at f to the machine. 100

Operation: Motion being given the machine in the direction from left to right, the traction wheel E will bear upon the surface to be swept and cause the gear F to rotate the pinion G and consequently the brush in 105 the opposite direction and the rapid revolutions of the brush will take up the dirt and dust and deposit it in the dirt pan J, which

when the operation of sweeping is performed may be emptied out of the box by means of the door *e*, as plainly shown in the figures.

5 In order to get a good and reliable traction or propelling power, and to prevent injury to carpets I have combined with the gears *F*, and *G*, the elastic traction wheel *H*, and by this combination have obtained 10 an effectual and reliable driving power for the brush without any liability to derangement or causing injury to the finest goods required to be swept.

During the wear of these machines it is 15 found necessary to adjust the brush both laterally and vertically, in order to keep it up to the segment *N*, and also against the floor or carpet in order to take up and carry forward the dirt. This I accomplish by 20 means of the plate *K*, (holding the brush boxes) and the screws which easily admit of the proper adjustment.

One great desideratum with these machines 25 is to prevent the dust from rising in sweeping, and for this purpose I employ a flexible curtain *L*, extending around three sides

of the machine which rests upon the surface to be swept and effectually prevents the egress of any dust.

The various parts of the machine and 30 method of securing the parts together are plainly shown in all the figures.

Having thus described my improved machine for sweeping carpeted and other surfaces, I will state what I claim and desire 35 to secure by Letters Patent—

1. I claim the combination of the gears *F* and *G*, with the driving wheel constructed and operating substantially as described and for the purposes specified. 40

2. The method of adjusting the brush by the plate *K*, which admits of both vertical and lateral adjustment as described and specified.

3. I also claim preventing the escape and 45 rising of the dust by means of the flexible curtain *L*, arranged and operating substantially as described and specified.

STEPH. WM. SMITH. [L.S.]
